United States Patent Office.

JACOB J. KISER, OF MIDDLETON, INDIANA.

Letters Patent No. 96,240, dated October 26, 1869.

IMPROVED RAILWAY-CAR BRAKE.

The Schedule referred to in these Letters Patent and making part of the same

To all whom it may concern:

Be it known that I, JACOB J. KISER, of Middleton, in the county of Henry, and State of Indiana, have invented certain new and useful Improvements in Car-Brakes; and I do hereby declare that the following is a full, clear, and exact description of the same, reference being had to the accompanying drawings, in which—

Figure 1 represents an elevation of the end of the body and truck of an ordinary car, showing the hand and foot brake-levers in the position they occupy when not in position to apply the brake.

Figure 2 represents a similar elevation, the hand and foot-levers being in the position they occupy when the brake is applied.

Figure 3 represents a plan or top view of one of the trucks of a car, the toggle-joint, and its several connecting-levers and arms, being in the position they occupy when the brake is applied.

Figure 4 represents a similar view, the parts occupying the positions when the brake is released.

Figure 5 represents an inverted view of one of the trucks of a car, the several parts occupying the position shown in fig. 4.

Figure 6 represents a cross-section of the central timbers of the truck, showing the vertical double-armed studs.

In the accompanying drawings, the body A of the car is supported upon two trucks, B, arranged at either end thereof, which may be of the ordinary construction, and connected to the car by the usual bolts C, so as to allow them to turn with the curve of the track.

The horizontal brake-bars D are arranged in the usual manner, and carry the rubbers a at the ends thereof, so that they may be brought in contact with and released from the periphery of the wheels of the truck, when operated by the braking-mechanism.

To the central horizontal connecting-timbers E of the truck, I secure two cross-plates F, to the projecting ends of which are affixed vertical studs b, which carry, at their upper and lower ends, oppositely-projecting arms e d.

To the ends of the lower arms d are connected the inner ends of two horizontal rods G, which latter are secured, at their outer ends, to the horizontal brake-bars D, by means of two screw-nuts e, fitted upon the said connecting-rods G, which are provided with screw-threads, so that the nuts e may be turned to adjust the brake-bars, and thus regulate them, to compensate for the wear of the rubbers or brake-blocks, and when the nuts are thus adjusted, they form a perfect lock of the connecting-rod G with the brake-bar.

The upper arms c of the vertical studs b are con-

nected to a horizontal connecting-rod, f, by means of two short arms g, in such manner as to constitute a single toggle-joint, located and arranged directly above the central horizontal timber E of the car-truck.

The opposite end of this toggle-joint connecting-rod f is united to a vertical crank-arm, I, on the end of a horizontal rock-shaft, J, located and fitted within bearings directly beneath the body of the car, and arranged parallel with the length thereof, so that its other end extends beyond the end of the car, and carries another crank-arm, K, arranged at right angles to the crank-arm I.

To the projecting end of this rock-shaft I a vertical hand-lever, L, is secured, which, as represented in the drawings, extends above the body of the car, and is fitted to move between a guide-rod, h, and the end of the car, at the top, so as to move from one side thereof to the other, while one side of the guide is provided with a ratchet-plate, M, located on one side of the car, into the teeth of which the said hand-lever L, when brought over to that side, is made to bite, and thus lock it in whatever position it may be brought in braking the cars.

The mechanism, thus arranged as described, is complete for a hand-lever brake; but, in connection therewith, I have arranged also a foot-lever brake, to be operated simultaneously therewith.

The mechanism of this foot-lever brake consists of a horizontal lever, N, hinged to the end or platform of the car, having a short and a long arm, the former of which is united to the outer crank-arm K by a link, i, while to the latter is connected a vertical rod, P, which extends, like the hand-lever, above the top of the car.

Its upper end is provided with a foot-hold or socket, p, and it is held in position by guides r, at the top and bottom of the car, which permit it to rise and fall freely.

The hand-lever L is located near the centre of the end of the car, while the foot-lever P is placed at the side, next the ratchet-plate M, and the two, thus arranged, act simultaneously to effect the braking of the cars.

This is an important feature, because it has been found, that even under ordinary circumstances, the hand-lever is not effectual, but, by the union of the two, so that the one may be operated by the hand, by the pulling strength of the brakeman, at the same instant the full weight of his body is united to that of his strength, and a double power is obtained.

When the brake is not in action, it will be seen that the hand-lever L occupies a position at one end of its guide, while the foot-lever P is at the opposite side of the car. In braking the cars, therefore, it is

not necessary for the attendant to seize the hand-lever L, and bring it over to the foot-lever P, but he makes for the foot-lever first, and, placing his foot into the upper socketed end p thereof, by his weight depresses it, which, by its connection with the double-cranked rock-shaft J below, automatically brings the hand-lever over to him, in a position that he may grasp it, and while still pressing with his foot, thus bring to bear the strength of his body, with that of his weight, until the end of the hand-lever is brought to the extreme end of the notched plate M, and the brake is perfect.

In thus operating the braking-mechanism, it will be seen that the hand L and the foot-lever P both unite in elevating the outer crank-arm K, which turns the rock-shaft J, so as to throw the inner crank-arm I toward the toggle-joint g, and through the rod f, connecting the two, force the toggle-arms g to assume a parallel position, or nearly so, which, through the arms c of the vertical studs b, causes the brake-bars to approach each other, so that their rubbers bear upon the wheels with a sudden and powerful force. While in this position, the hand-lever is locked with the ratchet-plate M, by reason of the inclination of the teeth, into which the lever fits, and the attendant may release his foot from the foot-lever, and leave the hand-lever in its locked position.

In releasing the brake, the hand-lever is simply thrown out of its lock with the ratchet-plate M, and the spring of the brake-bars will carry it over to its position at the opposite end of its guide, and at the same time elevate the foot-lever.

In this position of the several parts, the braking-bars are held away from the wheels without the use of springs, or any other device, simply by the inclined position of the lever, which, in connection with its weight, is also sufficient to hold the foot-lever up, in the proper position to brake the cars.

It is obvious that this braking-mechanism may be applied to either end of the car, if desired.

Having thus described my invention,

I claim—

1. The combination of a hand-lever, L, with a foot-lever, P, when arranged to operate simultaneously, to rotate the shaft J, substantially as before described.

2. A hand-lever, L, arranged to move in the arc of a circle, and a foot-lever, P, arranged to move vertically, when the latter is connected by the intermediate lever N, with the double-cranked rock-shaft J, substantially as before described.

3. The foot-lever P, when arranged to operate the hand-lever L, so as to bring the latter toward the lever P, and within the grasp of the attendant, in braking the cars, substantially as before described.

4. The combination and arrangement of the double-crank rock-shaft J, with the single toggle-joint g, when the latter is located between the central timber E of the truck and the body of the car, and connected to the braking-bars by the double-cranked studs b, substantially as before described.

5. The combination of the double-cranked rock-shaft J, the single toggle-joint g, with its connecting-rod f, and the hand and foot-levers L P, constructed, arranged, and operating substantially as before described.

6. The arrangement of the hand-lever L, in connection with the double-cranked rock-shaft J, in such manner, that when the brake is released, the weight of the hand-lever L, and its inclined position, will not only keep the brakes from the wheels, but the foot-lever P elevated, ready for action, substantially as before described.

JACOB J. KISER.
